UNITED STATES PATENT OFFICE.

VICTOR STANLEY WILLIAMS, OF LONDON, ENGLAND, ASSIGNOR OF ONE-HALF TO WILLIAMS ENGINEERING COMPANY LIMITED, OF LONDON, ENGLAND.

TYPE-CASTING MACHINE.

Application filed May 26, 1921. Serial No. 472,837.

To all whom it may concern:

Be it known that I, VICTOR STANLEY WILLIAMS, a subject of the King of Great Britain and Ireland, and residing at Nodis 5 Works, Julien Road, Northfields, Ealing, London, W., England, have invented certain new and useful Improvements in Type-Casting Machines of which the following is a specification.

This invention relates to type casting machines of the kind in which a pump or ram forces the metal from a heated metal pot through a nozzle into a mould which is periodically brought into position against the nozzle in order that a type may be cast and moved away therefrom, the matrix adapted to form the face of the type being moved away from the body of the mould and the mould parts being separated in order that the formed type may be separated from the tang and ejected, and in which the mould is arranged on a sliding carrier to which reciprocatory motion in a direction parallel with the longitudinal axis of the nozzle is imparted to bring it into position against the nozzle and to remove it therefrom, and means are associated with the mould carrier, adapted by the motion thereof to and from the nozzle to effect the bringing together and separation of the two halves of the mould and in some cases the presentation to and withdrawal of the matrix from the mould.

According to the invention, for effecting the bringing together and the separation of the mould parts, a toggle is connected to a prolongation of the mould block to which the upper portion of the mould is secured and to a fixed point on the mould carrier, the knuckle of the toggle being connected by suitable means with a fixed point on the machine.

For securing the two halves of the mould in position one against the other when the mould is against the nozzle, an abutment member may be provided against which the upper surface of the mould block is brought when the mould is in that position.

The mould block may, in such case, be provided with a surface inclined upwardly from the edge of the plate adjacent to the nozzle and a stud having a rounded face or a cavity in which a ball is rotatably mounted may be secured to a bracket on the machine in such manner that the mould carrier in its

travel towards the nozzle causes the face of the stud, or the ball mounted in the stud to co-operate with the inclined surface to secure the two portions of the mould together.

The stud may, if desired, be associated with a spring or other means adapted to cause it to press resiliently upon the mould block.

The mould block is preferably secured to the mould carrier by means adapted to permit the mould block to be turned about its longitudinal axis and thus to facilitate the inspection, cleaning, or other treatment of the face of the portion of the mould secured thereto.

The above referred to prolongation of the mould block may, for instance, be of circular cross-section and be rotatably and slidably mounted in a collar provided with pivots engaging holes in a bracket on the mould carrier and be associated with the means, as for instance, a toggle, adapted to rock the mould block about the aforesaid pivots to open and close the mould, by a connection adapted to permit of rotational motion of the mould block about its longitudinal axis and also to permit longitudinal motion in a direction parallel with said axis to permit of the position of the upper portion of the mould being varied relatively to the lower portion in accordance with the set width of the type to be cast.

Preferably, for ejecting the tang from the break parts, means operated by the motion of the sliding mould carrier is employed.

Thus, for example, an ejector, adapted to contact with the dot on the tang may be associated with the mould carrier and this ejector may be associated with a spring adapted to cause it to move against the dot, on the mould carrier receding from the nozzle, and with means adapted to be operated upon by a cam plate secured to a suitable fixed point on the machine as the mould carrier moves forward to cause the ejector to move against the action of the spring into its retracted position.

The ejector may be a knife secured to a bar sliding in guides provided on the face of the mould carrier adjacent to the nozzle on the melting pot; a helical spring may be arranged on this bar to draw the knife across the outer face of the break parts of the mould to eject the tang, while a member

adapted to co-operate with the cam to effect the retraction of the knife is connected with or forms part of the bar.

This member is conveniently formed by bending one end of the bar sharply downward in such manner that the cam plate may operate on this bent portion.

The member to which the matrix is secured is preferably slidably mounted in guides on the mould carrier and is, with advantage, adapted to be advanced towards the mould or retracted therefrom for the purpose of changing the matrix or for adjusting its position with a view to securing the desired close contact between the face of the matrix and the mould, or preventing the matrix being prematurely or too forcibly presented to the mould.

Thus, for instance, this member may comprise an internally screw-threaded sleeve arranged to slide in a guide provided on the mould carrier, an externally screw-threaded member to which the matrix is secured engaging the internally screw-threaded sleeve and means whereby the internally and externally screw-threaded members may be secured in fixed relation one with another, as for instance, by means of a second externally screw-threaded member engaging within the sleeve, the end of which member is adapted to bear upon the end of the other externally screw-threaded member which is within the sleeve.

For imparting the desired reciprocating motion to the sliding mould carrier a lever, for instance a bell crank lever, operated from a driving shaft may be employed.

Thus, for instance, the lever may be operated by a cam or eccentric arranged on the shaft operating the pump or ram for the molten metal and the end of the lever associated with the sliding carrier is conveniently engaged between spring pads suitably secured to the mould carrier.

Preferably, means are provided for increasing or decreasing the travel of the mould carrier. Such means may be constituted by a device adapted to vary the pressure on the aforementioned spring pads.

Thus, for instance, an externally screw-threaded rod may be arranged in a hole tapped in the sliding mould carrier, with one of its ends suitably cupped bearing upon the end of the spring of the spring pad remote from the metal pot.

For varying the speed of operation of the machine in accordance with the size of type to be produced which may, for example, vary from 6 point to 72 point any suitable change speed device may be employed; thus, for instance cone pulleys may be provided on the first motion shaft on the machine and on the shaft driven therefrom.

The machine in accordance with the invention is conveniently provided with means

whereby a variable dwell or period between the introduction of the metal into the mould and the ejection of the finished type may be secured, in order to allow a greater or less time for the metal to solidify according to the body size of the type being produced.

The pump or ram is preferably provided with an inlet or inlets for metal extending from the metal pot to an annular groove in the cylinder for the purpose of ensuring that the metal will be admitted thereto rapidly, and the cut off is preferably effected by the piston or ram in its downward stroke.

For causing the piston or ram to move downward, springs associated with the ram may, in accordance with the usual practice, be employed, a cam arranged on the driven shaft operating to raise the piston or ram against the action of the springs.

The jobber which effects the admission and cutoff of the supply of metal to the mould is preferably operated by fluid pressure as specified in the British application for Letters Patent No. 12213 of A. D. 1920, but a mechanically operated jobber may if desired be provided.

A type casting machine in accordance with the invention is illustrated by way of example in the accompanying drawings, in which:—

Figure 1 is a front elevation of a type casting machine in accordance with the invention.

Figure 2 is a plan corresponding with Figure 1, and

Figures 3 and 4 are elevations viewed from the right and left hand sides of Figure 1 respectively.

Figure 5 is a section on a larger scale of the mould carrier.

Figure 6 is a section showing the construction of the pump.

Figure 7 is a section through the metal pot, the pump therein and the nozzle.

Figure 8 is a view in plan, and

Figure 9 is a view in section of the dwell gear employed for periodically interrupting the operation of the pump and the motion of the mould carrier to permit the metal injected in the mould to harden.

In the drawings 1 is a sliding mould carrier engaged on a dove-tailed slide 2 forming part of the casting 3 mounted upon the main casting of the machine 4. Reciprocatory motion is imparted to the sliding mould carrier in order to bring it into position against the nozzle 5 (see Figures 2 to 4 and 7) by means of bell crank lever 6 pivoted at 7 and provided with a roller 8 contacting with the cam 9 (see Figures 1 and 2). One arm of the bell crank lever is provided with a spherical end 10 (see Figure 5) engaged between pads 11 and 12 secured to the mould carrier, one of these pads

being associated with a helical spring 13 arranged in the screw bush 14 by the adjustment of which the mould carrier and therefore the mould can be caused to be forced more or less firmly against the nozzle, associated with which in the usual way is a dot plate 15, more clearly shown in Figure 7, provided with a coned aperture 16 which dot plate is suspended from the pin 17.

For effecting the presentation to and withdrawal of the matrix from the mould a lever 18 is connected with a member 19 carrying a matrix 20 (see Figure 5). This lever is pivoted at 21 to the mould carrier and is also connected by means of a spring 22 with a fixed point on the machine so that the motion of the carrier away from the nozzle will cause the matrix to be withdrawn from the mould while motion in the reverse direction will cause the matrix to be presented to the mould. The member carrying the matrix is slidably mounted in a guide 23 on the mould carrier and is adapted to be advanced towards the mould or retracted therefrom for the purpose of changing the matrix or for adjusting its position with a view to securing the desired close contact between the face of the matrix and the mould or preventing the matrix being prematurely or too forcibly presented to the mould and it comprises an internally screw-threaded sleeve in which an externally screw-threaded member 24 to which the matrix is secured is engaged, while a second externally screw-threaded member 25 is engaged within the sleeve the end of which member is adapted to bear upon the end of the other externally screw-threaded member within the sleeve and thus to secure the said member in the axial position relative to the member 19 in which it has been adjusted by the rotation of the member 19.

The mould block 26 to which the upper half of the mould is secured is provided with passages through which water may be circulated for cooling the mould block. A prolongation 27 is provided on the mould block. This prolongation is of circular cross-section and is mounted in one arm of the L-shaped member 28 so that it may be turned about its longitudinal axis to facilitate the inspection, cleaning or other treatment of the face of the portion of the mould secured thereto, and also to permit longitudinal motion in a direction parallel with its axis to permit the position of the upper portion of the mould being varied relatively to the lower portion, in accordance with the set width of the type to be cast, the bolt 29 being provided to enable the mould block to be secured in the desired position.

The L-shaped member is provided with pivots 30, 30^a, engaged in holes in the bracket 31 on the sliding carrier for the mould, a prolongation 32 on the said mem-

ber being engaged in a collar 33 provided with pivots 34, 34^a engaged in holes in the link 35, which is pivoted to the lever 36 capable of oscillation about the fulcrum 37 secured to the sliding mould carrier, the link and lever functioning as a toggle serving to open and close the mould in consequence of the motion of the mould carrier toward or away from the nozzle, the lever being also connected to the stud 38 on the machine by means of the rod 39 which is screw-threaded at 40 and engaged in the nut 41 pivoted to the end of the lever, so that the length of the connection between the stud and the end of the lever may be varied for the purpose of adjusting the degree to which the mould is opened.

When the mould carrier is in position against the nozzle, the upper mould block will be in the closed position in which it will be retained during the casting operation and subsequent dwell, if any, to permit the metal to cool by means of the abutment member constituted by a ball 42 mounted in the cup 43 on the end of the screw 44 secured in the bracket 45 in which it may be rotated so as to increase or decrease its effective length, a lock nut 46 being provided to secure it in any given position. One edge of the mould block may be bevelled or provided with a hardened plate as at 47 adapted to be brought under the ball.

For ejecting the tang from the break parts of the mould an ejector knife 48 is pivoted at 49 to one face of the sliding mould carrier and this knife is connected by the link 50 to the lever 51 secured to one of the pivots of the L-shaped member 28, so that when this member is rocked consequent on the mould carrier being retracted from the nozzle, the ejector knife will be moved about its pivot and caused to strike the dot on the tang and eject the latter.

On the shaft on which the cam operating the bell-crank lever causing the desired motion of the mould carrier is mounted, a second cam 52 is mounted. A roller 53 secured to the member 54 slidably mounted in a guide 55 on the main casting of the machine bears upon the cam. The said member (see Figure 6) is provided with a socket 56 forming a bearing for the spherical end of the pin 57, one end of which is engaged in the rod 58 which is screw-threaded at 59 and engaged by a nut 60, between the upper surface of which and the lower surface of the guide 61 a spring 62 is inserted and operates to force the rod in a downward direction against the action of the cam. The rod near its upper end is provided with a spherical surfaced portion 63 engaged in a tubular bearing member 64 slidably mounted in the guide 61. The object of these spherical bearing surfaces is

to prevent the rod operating the pump being subjected to undesirable stresses which might cause it to seize due to the deformation of the metal pot and the main casting by heat. The rod 58 is connected by a yoke piece 65 guided on the pin 66 with the screwed sleeve 67 in which the rod 68 is engaged, so that by relative rotation of the rod and sleeve the stroke of the piston or 10 ram may be varied. The aforesaid rod is connected with the piston or ram 69 by a pin 70 engaging holes therein and passing loosely through a hole in the rod, and the ram is provided near its base with a screw-threaded portion enabling it to be screwed 15 into the sleeve 71, as shown in Figure 6 of the drawings, in which case the ram and sleeve will be operated by the rod as a single element and form a ram adapted for dis- 20 placing a considerable body of metal. When on the other hand the ram is disengaged from the sleeve and the latter is inhibited from motion by means of the locking plate 72 and the screw 73, the ram will 25 be reciprocated within the sleeve and will operate to displace a less body of metal such as would be required in forming type of smaller sizes.

The ram operates in the cylinder 74, 30 which is connected with the duct 75 in which a valve 76 is provided for admitting metal to the pump from the metal pot 77, the duct terminating in the working chamber 78 of the nozzle. The jobber 79 is arranged 35 within this working chamber and is provided with a piston face 80, so proportioned that the metal admitted to the chamber will cause the jobber to move into the retracted position to permit the discharge of 40 metal through the nozzle. For causing the jobber to move into the forward position to close the nozzle, a spring 81 is arranged between one end of the lever 82 pivoted on the lug 83 formed on the casting constituting the metal pot, the other end of the lever bearing upon the prolongation 84 of the jobber extending inwardly into the metal pot. A nut 85 is arranged on the externally 45 screw-threaded rod 86 for varying the degree of compression on the spring to enable a greater or less degree of pressure to be brought to bear upon the jobber to close the same when the pressure on the metal in the pump is relieved on the upward stroke 50 of the piston or ram. The means whereby a variable dwell or period between the introduction of the metal into the mould and the ejection of the finished type is secured may in part be seen in Figures 1 and 2, 55 but is shown on a larger scale in Figures 3 and 9, to which figures reference will be made in the following description.

The shaft 87 on which the cams operating the sliding mould carrier and pump are 60 mounted is provided with a toothed wheel

88 rigidly secured thereto by the pin 89. This wheel engages a pinion 90 rotatably mounted on the shaft 91, but secured from axial motion thereon, the shaft being provided with a cone pulley 92 which may be 70 driven from a cone pulley on a first motion shaft, not shown, arranged in bearing in the standard on which the machine is mounted.

The aforesaid pinion is provided on either side with dog clutch members 93, 94, the former of which may be engaged by the dog clutch member 95 adapted to be moved into or out of engagement by the lever 96 and to cause the machine to operate without a dwell or a dwell of only 75 short duration.

The dog clutch member 94 is adapted to be engaged by the dog clutch member 97 formed on the sleeve 98 slidably mounted on the shaft 91, but secured from rotation relative thereto by the feather 99. This sleeve is provided with a circumferential flange 100 against which a roller 101 mounted on the lever 102 pivoted to the machine frame and operated upon by a spring 103, bears, so as to cause the sleeve to be retracted and the clutch to be disengaged when the block 104 is moved out of engagement with the groove 105. This block is secured to the lever 106 pivoted at 107 in a bracket 108 secured to the main casting of the machine and is associated with a spring 109 adapted to draw it forward into engagement with the groove. The block referred to is moved out of engagement with the groove under the action of the finger 110 secured on the rod 111 consequent on the latter being rotated by the boss 112 on the toothed wheel being caused to contact with a second finger 113. When the sleeve is released and is retracted under the action of the lever and spring it will be caused to strike a third finger 114 secured on the rod 115 slidably mounted in a hole 116 drilled in the first mentioned rod, a key-hole slot being provided in the side of this rod adapted to act as a bayonet catch for the said finger, a spring 117 being arranged to cause the said rod to move into the retracted position when it is released.

With this arrangement, the sleeve when it is retracted will engage the finger 114 in one of two positions thus causing it to retract the rod 111 and disengage the finger 113 from the boss 112 and at the same time the finger 110 is released from the lever 106; the block 104 on which engages the screw-threaded portion of the sleeve the rotation of which by the shaft on which it is mounted will cause it to move axially, thus effecting engagement of the clutch elements at intervals which will vary according to which of the turns of the screw-thread is engaged by the block.

The lever 118 is pivoted at 119 and is provided with an inclined plane 120 contacting with the end of the rod 121 provided with a spherical head 122 engaging a hole in the lever 106 and according to the position of the lever 118 the position of the lever 106 will be changed in opposition to the action of the spring 109 so as to retain the block 104 out of engagement with the sleeve as 10 would be necessary should the other clutch element 95 be in engagement. For the purpose of securing the clutch operating levers in the desired positions a plate 123 mounted on posts 124, 124^a and associated with 15 springs 125 and 125^a is provided.

Having now described my invention, what I claim as new and desire to secure by Letters Patent is:—

1. A type casting machine comprising a metal pot, a nozzle, a pump associated with the nozzle adapted to deliver metal from the metal pot through the nozzle, upper and lower mould blocks constituting a mould adapted to receive the metal, so delivered, a sliding carrier engaging the mould, means adapted to impart reciprocatory motion to the sliding carrier in a direction parallel with the longitudinal axis of the nozzle to bring the mould into position against the nozzle and to remove it therefrom, a prolongation on the upper mould block, a toggle connected to the prolongation and to a fixed point on the mould carrier, means connecting the knuckle of the toggle to a fixed point on the machine adapted to secure the separation of the upper and lower mould blocks on the motion of the mould carrier away from the nozzle and the bringing together of the mould blocks by motion toward the nozzle.
2. A type casting machine comprising a metal pot, a nozzle, a pump associated with the nozzle adapted to deliver metal from the metal pot through the nozzle, upper and lower mould blocks constituting a mould adapted to receive the metal so delivered, a sliding carrier engaging the mould, means adapted to impart reciprocatory motion to the sliding carrier in a direction parallel with the longitudinal axis of the nozzle to bring the mould into position against the nozzle and to remove it therefrom, a prolongation on the upper mould block, a toggle connected to the prolongation and to a fixed point on the mould carrier, means connecting the knuckle of the toggle to a fixed point on the machine adapted to secure the separation of the upper and lower mould blocks on the motion of the mould carrier away from the nozzle and the bringing together of the mould blocks by motion toward the nozzle, and a matrix, a member carrying the matrix, a lever associated with the member and with a fixed point on the machine, and a fulcrum on the mould car-
- rier for said lever adapted by the motion of the mould carrier toward the nozzle to bring the matrix into position against the mould and by motion of the mould carrier away from the nozzle to effect withdrawal of the matrix from the mould.
3. A type casting machine comprising a metal pot, a nozzle, a pump associated with the nozzle adapted to deliver metal from the metal pot through the nozzle, upper and lower mould blocks constituting a mould adapted to receive the metal so delivered, a sliding carrier engaging the mould, means adapted to impart reciprocatory motion to the sliding carrier in a direction parallel with the longitudinal axis of the nozzle to bring the mould into position against the nozzle and to remove it therefrom, a prolongation on the upper mould block, a toggle connected to the prolongation and to a fixed point on the mould carrier, means connecting the knuckle of the toggle to a fixed point on the machine adapted to secure the separation of the upper and lower mould blocks on the motion of the mould carrier away from the nozzle and the bringing together of the mould blocks by motion toward the nozzle, an internally screw-threaded sleeve, a guide on the mould carrier engaging said sleeve, an externally screw-threaded member mounted within the internally screw-threaded sleeve and adapted to engage the matrix and means whereby the internally screw-threaded sleeve and the externally screw-threaded member may be secured in fixed relation one to the other.
4. A type casting machine comprising a metal pot, a nozzle, a pump associated with the nozzle adapted to deliver metal from the metal pot through the nozzle, upper and lower mould blocks constituting a mould adapted to receive the metal so delivered, a sliding carrier engaging the mould, means adapted to impart reciprocatory motion to the sliding carrier in a direction parallel with the longitudinal axis of the nozzle to bring the mould into position against the nozzle and remove it therefrom, a prolongation on the upper mould block, a toggle connected to the prolongation and to a fixed point on the mould carrier, means connecting the knuckle of the toggle to a fixed point on the machine adapted to secure the separation of the upper and lower mould blocks on the motion of the mould carrier away from the nozzle and the bringing together of the mould blocks by motion between the nozzle, an internally screw-threaded sleeve, a guide on the mould carrier engaging said sleeve, an externally screw-threaded member mounted within the internally screw-threaded sleeve and adapted to engage the matrix, and a second externally screw-threaded member engaging within the sleeve, the end of said member being adapt-

ed to bear upon the end of the other externally screw-threaded member engaging within the sleeve.

5. A type casting machine comprising a metal pot, a nozzle, a pump associated with the nozzle adapted to deliver metal from the metal pot through the nozzle, upper and lower mould blocks constituting a mould adapted to receive the metal so delivered, a sliding carrier engaging the mould, means adapted to impart reciprocatory motion to the sliding carrier in a direction parallel with the longitudinal axis of the nozzle to bring the mould into position against the nozzle and to remove it therefrom, a prolongation on the upper mould block, a toggle connected to the prolongation and to a fixed point on the mould carrier, means connecting the knuckle of the toggle to a fixed point on the machine adapted to secure the separation of the upper and lower mould blocks on the motion of the mould carrier away from the nozzle and the bringing together of the mould blocks by motion toward the nozzle, and means operated by the motion of the sliding mould carrier adapted to eject the tang formed in casting the type.

6. A type casting machine comprising a metal pot, a nozzle, a pump associated with the nozzle adapted to deliver metal from the metal pot through the nozzle, upper and lower mould blocks constituting a mould adapted to receive the metal so delivered, a sliding carrier engaging the mould, means adapted to impart reciprocatory motion to the sliding carrier in a direction parallel with the longitudinal axis of the nozzle to bring the mould into position against the nozzle and to remove it therefrom, a prolongation on the upper mould block, a toggle connected to the prolongation and to a fixed point on the mould carrier, means connecting the knuckle of the toggle to a fixed point on the machine adapted to secure the separation of the upper and lower mould blocks on the motion of the mould carrier away from the nozzle and the bringing together of the mould blocks by motion toward the nozzle, and a matrix, a member carrying the matrix, a lever associated with the member and with a fixed point on the machine, a fulcrum on the mould carrier for said lever adapted by the motion of the mould carrier toward the nozzle to bring the matrix into position against the mould and by motion of the mould carrier away from the nozzle to effect withdrawal of the matrix from the mould and means operated by the motion of the sliding mould carrier adapted to eject the tang formed in casting the type.

7. A type casting machine comprising a metal pot, a nozzle, a pump associated with the nozzle adapted to deliver metal from the metal pot through the nozzle, upper and lower mould blocks constituting a mould

adapted to receive the metal so delivered, a sliding carrier engaging the mould, means adapted to impart reciprocatory motion to the sliding carrier in a direction parallel with the longitudinal axis of the nozzle to bring the mould into position against the nozzle and to remove it therefrom, a prolongation on the upper mould block, a toggle connected to the prolongation and to a fixed point on the mould carrier, means connecting the knuckle of the toggle to a fixed point on the machine adapted to secure the separation of the upper and lower mould blocks on the motion of the mould carrier away from the nozzle and the bringing together of the mould blocks by motion toward the nozzle, an internally screw-threaded sleeve, a guide on the mould carrier engaging said sleeve, an externally screw-threaded member mounted within the internally screw-threaded sleeve and adapted to engage the matrix, means whereby the internally screw-threaded sleeve and the externally screw-threaded member may be secured in fixed relation one to the other, and means operated by the motion of the sliding mould carrier adapted to eject the tang formed in casting the type.

8. A type casting machine comprising a metal pot, a nozzle, a pump associated with the nozzle adapted to deliver metal from the metal pot through the nozzle, upper and lower mould blocks constituting a mould adapted to receive the metal so delivered, a sliding carrier engaging the mould, means adapted to impart reciprocatory motion to the sliding carrier in a direction parallel with the longitudinal axis of the nozzle to bring the mould into position against the nozzle and remove it therefrom, a prolongation on the upper mould block, a toggle connected to the prolongation and to a fixed point on the mould carrier, means connecting the knuckle of the toggle to a fixed point on the machine adapted to secure the separation of the upper and lower mould blocks on the motion of the mould carrier away from the nozzle and the bringing together of the mould blocks by motion toward the nozzle, an internally screw-threaded sleeve, a guide on the mould carrier engaging said sleeve, an externally screw-threaded member mounted within the internally screw-threaded sleeve and adapted to engage the matrix, a second externally screw-threaded member engaging within the sleeve, the end of said member being adapted to bear upon the end of the other externally screw-threaded member engaging within the sleeve and means operated by the motion of the sliding mould carrier adapted to eject the tang formed in casting the type.

9. A type casting machine comprising a metal pot, a nozzle, a pump associated with the nozzle adapted to deliver metal from

the metal pot through the nozzle, upper and lower mould blocks constituting a mould adapted to receive the metal so delivered, a sliding carrier engaging the mould, means adapted to impart reciprocatory motion to the sliding carrier in a direction parallel with the longitudinal axis of the nozzle to bring the mould into position against the nozzle and to remove it therefrom, a prolongation on the upper mould block, a toggle connected to the prolongation and to a fixed point on the mould carrier, means connecting the knuckle of the toggle to a fixed point on the machine adapted to secure the separation of the upper and lower mould blocks on the motion of the mould carrier away from the nozzle and the bringing together of the mould blocks by motion toward the nozzle, a lever engaging the mould carrier, a shaft, a cam on the shaft adapted to operate the lever to effect reciprocation of the mould carrier and a cam on said shaft adapted to operate the pump.

10. A type casting machine comprising a metal pot, a nozzle, a pump associated with the nozzle adapted to deliver metal from the metal pot through the nozzle, upper and lower mould blocks constituting a mould adapted to receive the metal so delivered, a sliding carrier engaging the mould, means adapted to impart reciprocatory motion to the sliding carrier in a direction parallel with the longitudinal axis of the nozzle to bring the mould into position against the nozzle and to remove it therefrom, a prolongation on the upper mould block, a toggle connected to the prolongation and to a fixed point on the mould carrier, means connecting the knuckle of the toggle to a fixed point on the machine adapted to secure the separation of the upper and lower mould blocks on the motion of the mould carrier away from the nozzle and the bringing together of the mould blocks by motion toward the nozzle, and a matrix, a member carrying the matrix, a lever associated with the member and with a fixed point on the machine, a fulcrum on the mould carrier for said lever adapted by the motion of the mould carrier toward the nozzle to bring the matrix into position against the mould and by motion of the mould carrier away from the nozzle to effect withdrawal of the matrix from the mould, a lever engaging the mould carrier, a shaft, a cam on the shaft adapted to operate the lever to effect reciprocation of the mould carrier and a cam on said shaft adapted to operate the pump.

11. A type casting machine comprising a metal pot, a nozzle, a pump associated with the nozzle adapted to deliver metal from the metal pot through the nozzle, upper and lower mould blocks constituting a mould adapted to receive the metal so delivered, a sliding carrier engaging the mould, means

adapted to impart reciprocatory motion to the sliding carrier in a direction parallel with the longitudinal axis of the nozzle to bring the mould into position against the nozzle and to remove it therefrom, a prolongation on the upper mould block, a toggle connected to the prolongation and to a fixed point on the mould carrier, means connecting the knuckle of the toggle to a fixed point on the machine adapted to secure the separation of the upper and lower mould blocks on the motion of the mould carrier away from the nozzle and the bringing together of the mould blocks by motion toward the nozzle, an internally screw-threaded sleeve, a guide on the mould carrier engaging said sleeve, an externally screw-threaded member mounted within the internally screw-threaded sleeve and adapted to engage the matrix, means whereby the internally screw-threaded sleeve and the externally screw-threaded member may be secured in fixed relation one to the other, a lever engaging the mould carrier, a shaft, a cam on the shaft adapted to operate the lever to effect reciprocation of the mould carrier and a cam on said shaft adapted to operate the pump.

12. A type casting machine comprising a metal pot, a nozzle, a pump associated with the nozzle adapted to deliver metal from the metal pot through the nozzle, upper and lower mould blocks constituting a mould adapted to receive the metal so delivered, a sliding carrier engaging the mould, means adapted to impart reciprocatory motion to the sliding carrier in a direction parallel with the longitudinal axis of the nozzle to bring the mould into position against the nozzle and remove it therefrom, a prolongation on the upper mould block, a toggle connected to the prolongation and to a fixed point on the mould carrier, means connecting the knuckle of the toggle to a fixed point on the machine adapted to secure the separation of the upper and lower mould blocks on the motion of the mould carrier away from the nozzle and the bringing together of the mould blocks by motion toward the nozzle, an internally screw-threaded sleeve, a guide on the mould carrier engaging said sleeve, an externally screw-threaded member mounted within the internally screw-threaded sleeve and adapted to engage the matrix, a second externally screw-threaded member engaging within the sleeve, the end of said member being adapted to bear upon the end of the other externally screw-threaded member engaging within the sleeve, a lever engaging the mould carrier, a shaft, a cam on the shaft adapted to operate the lever to effect reciprocation of the mould carrier and a cam on said shaft adapted to operate the pump.

13. A type casting machine comprising a

metal pot, a nozzle, a pump associated with the nozzle adapted to deliver metal from the metal pot through the nozzle, upper and lower mould blocks constituting a mould adapted to receive the metal so delivered, a sliding carrier engaging the mould, means adapted to impart reciprocatory motion to the sliding carrier in a direction parallel with the longitudinal axis of the nozzle to bring the mould into position against the nozzle and to remove it therefrom, a prolongation on the upper mould block, a toggle connected to the prolongation and to a fixed point on the mould carrier, means connecting the knuckle of the toggle to a fixed point on the machine adapted to secure the separation of the upper and lower mould blocks on the motion of the mould carrier away from the nozzle and the bringing together of the mould blocks by motion toward the nozzle, means operated by the motion of the sliding mould carrier adapted to eject the tang formed in casting the type, a lever engaging the mould carrier, a shaft, a cam on the shaft adapted to operate the lever to effect reciprocation of the mould carrier and a cam on said shaft adapted to operate the pump.

14. A type casting machine comprising a metal pot, a nozzle, a pump associated with the nozzle adapted to deliver metal from the metal pot through the nozzle, upper and lower mould blocks constituting a mould adapted to receive the metal so delivered, a sliding carrier engaging the mould, means adapted to impart reciprocatory motion to the sliding carrier in a direction parallel with the longitudinal axis of the nozzle to bring the mould into position against the nozzle and to remove it therefrom, a prolongation on the upper mould block, a toggle connected to the prolongation and to a fixed point on the mould carrier, means connecting the knuckle of the toggle to a fixed point on the machine adapted to secure the separation of the upper and lower mould blocks on the motion of the mould carrier away from the nozzle and the bringing together of the mould blocks by motion toward the nozzle, and a matrix, a member carrying the matrix, a lever associated with the member and with a fixed point on the machine, a fulcrum on the mould carrier for said lever adapted by the motion of the mould carrier toward the nozzle to bring the matrix into position against the mould and by motion of the mould carrier away from the nozzle to effect withdrawal of the matrix from the mould, means operated by the motion of the sliding mould carrier adapted to eject the tang formed in casting the type, a lever engaging the mould carrier, a shaft, a cam on the shaft adapted to operate the lever to effect reciprocation of the mould carrier and a

cam on said shaft adapted to operate the pump.

15. A type casting machine comprising a metal pot, a nozzle, a pump associated with the nozzle adapted to deliver metal from the metal pot through the nozzle, upper and lower mould blocks constituting a mould adapted to receive the metal so delivered, a sliding carrier engaging the mould, means adapted to impart reciprocatory motion to the sliding carrier in a direction parallel with the longitudinal axis of the nozzle to bring the mould into position against the nozzle and to remove it therefrom, a prolongation on the upper mould block, a toggle connected to the prolongation and to a fixed point on the mould carrier, means connecting the knuckle of the toggle to a fixed point on the machine adapted to secure the separation of the upper and lower mould blocks on the motion of the mould carrier away from the nozzle and the bringing together of the mould blocks by motion toward the nozzle, an internally screw-threaded sleeve, a guide on the mould carrier engaging said sleeve, an externally screw-threaded member mounted within the internally screw-threaded sleeve and adapted to engage the matrix, means whereby the internally screw-threaded sleeve and the externally screw-threaded member may be secured in fixed relation one to the other, means operated by the motion of the sliding mould carrier adapted to eject the tang formed in casting the type, a lever engaging the mould carrier, a shaft, a cam on the shaft adapted to operate the lever to effect reciprocation of the mould carrier and a cam on said shaft adapted to operate the pump.

16. A type casting machine comprising a metal pot, a nozzle, a pump associated with the nozzle adapted to deliver metal from the metal pot through the nozzle, upper and lower mould blocks constituting a mould adapted to receive the metal so delivered, a sliding carrier engaging the mould, means adapted to impart reciprocatory motion to the sliding carrier in a direction parallel with the longitudinal axis of the nozzle to bring the mould into position against the nozzle and remove it therefrom, a prolongation on the upper mould block, a toggle connected to the prolongation and to a fixed point on the mould carrier, means connecting the knuckle of the toggle to a fixed point on the machine adapted to secure the separation of the upper and lower mould blocks on the motion of the mould carrier away from the nozzle and the bringing together of the mould blocks by motion toward the nozzle, an internally screw-threaded sleeve, a guide on the mould carrier engaging said sleeve, an externally screw-threaded member mounted within the internally screw-threaded

ed sleeve and adapted to engage the matrix, a second externally screw-threaded member engaging within the sleeve, the end of said member being adapted to bear upon the end 5 of the other externally screw-threaded member engaging within the sleeve, means operated by the motion of the sliding mould carrier adapted to eject the tang formed in

casting the type, a lever engaging the mould carrier, a shaft, a cam on the shaft adapted 10 to operate the lever to effect reciprocation of the mould carrier and a cam on said shaft adapted to operate the pump.

In testimony whereof I have signed my name to this specification.

VICTOR STANLEY WILLIAMS.
